The ornamental design for a combined impact valve and plunger, as shown and described.

DESCRIPTION

FIG. 1 is a perspective view of an impact valve plug and plunger assembly showing my new design;

FIG. 2 is a side view of a combined impact valve and plunger, the opposite side being a mirror image thereof; FIG. 3 is a plunger end view of a combined impact valve and plunger with a valve body and housing shown in broken lines;

FIG. 4 is a plug end view of a combined impact valve and plunger with a valve body and housing shown in broken lines;

FIG. 5 is a plunger end view of a combined impact valve and plunger; and

FIG. 6 is a plug end view of a combined impact valve and plunger.

The broken lines showing of a valve body and housing is for illustrative purposes only and forms no part of the claimed design.
